UNITED STATES PATENT OFFICE.

WILFRED D. CHESTER, OF SEWICKLEY, PENNSYLVANIA, ASSIGNOR TO THE BABCOCK & WILCOX COMPANY, OF BAYONNE, NEW JERSEY, A CORPORATION OF NEW JERSEY.

WATER-TUBE BOILER.

1,124,392.

Specification of Letters Patent.

Patented Jan. 12, 1915.

Application filed May 31, 1911. Serial No. 630,476.

To all whom it may concern:

Be it known that I, WILFRED D. CHESTER, a citizen of the United States, residing at Sewickley, in the county of Allegheny and State of Pennsylvania, have invented certain new and useful Improvements in Water-Tube Boilers, of which the following is a specification.

The object of the present invention is to provide means for the economic renewal of those tubes of a water tube boiler which are directly exposed to the heat of the furnace gases, and it will be understood by reference to the accompanying drawings in which—

Figure 1 is a longitudinal section through a boiler showing the adaptation of my invention thereto; Fig. 2 a view showing a slight modification, and Fig. 3 a detail view.

Similar reference numerals indicate similar parts in the several views.

The standard type of boiler shown in Fig. 1 comprises a bank of inclined water tubes 1 connected to uptake and downtake headers 2 and 3, respectively. The bank is divided into three vertical passes by baffles 4 and 5, the former in contact with the bridge wall 6 of the furnace 7. The gases from the furnace flow upwardly through the first pass at the uptake end of the tubes, downwardly through the second pass, and then upwardly through the third pass to the stack outlet.

It has been the practice heretofore to use tubes extending from the uptake to the downtake header. The tubes of the lowermost row, being those subjected to the direct heat of the furnace gases, are the first to deteriorate and their renewal requires the removal of the entire tube, although the portion of the tube back of the bridge wall may be in good condition. To minimize the cost of tube renewals I have suggested various expedients disclosed in applications filed of even date herewith. In the present arrangement I use short tubes for the lower row of the bank extending from the uptake headers to a point beyond the bridge wall and there connecting them through boxes and other short tubes to the downtake headers. Thus, in Fig. 1, the tubes 8 of the lowermost row extend from the uptake header 2 to a point back of the bridge wall where they are expanded into a box 9. This box is nipped to a box 10, which, in turn, is connected by short tubes 11 to the downtake headers 3. The boxes 9 and 10 may

be installed as units or in sections, a hand hole cap 12 being placed opposite each tube end, the bridge wall being so designed, and the boxes placed in such position as to admit the use of an expander for all joints. Also 60 as shown, the bridge wall 6 extends upwardly to the short tube lengths 8 and is immediately below the transverse baffle 4.

The slight modification shown in Fig. 2 consists in lengthening the nipple 13 connecting the two boxes 9 and 10, and placing it in a substantially vertical position, and using substantially straight tubes 14 between the box 10 and the rear header 3, these tubes being bent only at their point of 70 connection with said header. With this arrangement, as in others proposed by me, short tubes may be used for the lower row. Not only does this minimize the cost of tubes which require most frequent renewal, but, in 75 the renewing, there is no disturbance of the rear baffle 5. This is because of the termination of the tubes 8 at a point in the second pass.

What I claim and desire to secure by Letters Patent of the United States is:

1. A water tube boiler comprising a bank of inclined generating tubes, uptake and downtake headers into which said tubes are expanded, a furnace below the uptake ends 85 of the tubes, a bridge wall for said furnace extending upwardly to the lowermost row of tubes of the bank, said lowermost row consisting of short tube lengths extending from the uptake header to a point immediately back of the bridge wall, a transverse box to which the ends of said tubes are connected, a second transverse box below and nipped to the first named box, and tubes connecting said second named box with 90 the downtake headers, said boxes being provided with hand hole fittings opposite the tube ends for accessibility to the tubes and for use in expanding the tubes.

2. A water tube boiler comprising a bank 100 of inclined generating tubes, uptake and downtake headers into which said tubes are expanded, transverse baffles dividing said bank of tubes into a plurality of passes beginning at the steam uptake end, a furnace 105 below the first pass, a bridge wall for said furnace extending upwardly to the lowermost row of tubes and immediately below the first transverse baffle, the lowermost row of said bank consisting of short tube lengths 110

extending from the uptake header to a point immediately back of the bridge wall, a transverse box to which the ends of said tubes are connected, a second transverse box 5 below and nipped to said first named box, and tubes connecting said second named box with the downtake headers said boxes being provided with hand hole fittings opposite the tube ends for accessibility to the tubes and for use in expanding the tubes.

3. A water tube boiler comprising a bank of inclined generating tubes, uptake and downtake headers into which said tubes are expanded, a furnace below the uptake 15 ends of the tubes, a bridge wall for said furnace extending upwardly to the lowermost row of tubes of the bank, said lowermost row consisting of short tube lengths extending from the uptake header to a point 20 immediately back of the bridge wall, a transverse box to which the ends of said tubes are connected, a second transverse box nipped to the first named box, and tubes connecting said boxes with the boiler circulation, 25 said boxes being provided with hand hole fittings opposite the tube ends for accessibility to the tubes and for use in expanding the tubes.

4. A water tube boiler comprising a bank of inclined generating tubes, uptake and 30 downtake headers into which said tubes are expanded, transverse baffles dividing said bank of tubes into a plurality of passes beginning at the steam uptake end, a furnace below the first pass, a bridge wall for said 35 furnace extending upwardly to the lowermost row of tubes and immediately below the first transverse baffle, the lowermost row of said bank consisting of short tube lengths 40 extending from the uptake header to a point immediately back of the bridge wall, a transverse box to which the ends of said tubes are connected, a second transverse box nipped to the first named box, and tubes connecting 45 said boxes with the boiler circulation, said boxes being provided with hand hole fittings opposite the tube ends for accessibility to the tubes and for use in expanding the tubes.

In testimony whereof I have hereunto signed my name in the presence of two subscribing witnesses.

WILFRED D. CHESTER.
